W. G. KENDALL,
VANITY BOX,
APPLICATION FILED MAY 6, 1916.

1,209,168.

Patented Dec. 19, 1916.

Inventor
W. G. Kendall.

By

Mark Weers, Attorney

UNITED STATES PATENT OFFICE.

WILLIAM G. KENDALL, OF NEWARK, NEW JERSEY.

VANITY-BOX.

1,209,168.

Specification of Letters Patent. Patented Dec. 19, 1916.

Application filed May 6, 1916. Serial No. 95,902.

To all whom it may concern:

Be it known that I, WILLIAM G. KENDALL, a citizen of the United States, residing at Newark, in the county of Essex and State of New Jersey, have invented certain new and useful Improvements in Vanity-Boxes, of which the following is a specification.

My invention relates to new and useful improvements in vanity boxes, the primary object of my invention being the provision of a vanity box adapted to lockingly and detachably receive a rouge holding pad in such a manner that when the rouge has been used from the pad, the empty pad may be removed and replaced by a fresh one.

A still further object of my invention consists in providing an anchoring means for the pad of such a nature that the box may be economically manufactured and yet durable in construction.

Another object which I have in view consists in the construction of a vanity box in which a mirror forms the bottom of the box, the rouge holding pad being anchored in place against the mirror and in turn serving to anchor the mirror.

Another object which I have in view is the provision of a box having a hinged cover in which the hinge is struck out wholly from the box and not separately formed and in which the hinge is so arranged that the cover, in open position, is supported vertically or substantially so. With a box of this type, I preferably mount a mirror in the cover as it will be readily accessible for use, due to the position in which the cover is supported when the box is open.

With these and other objects in view, my invention will be more fully described, illustrated in the accompanying drawing, and then specifically pointed out in the claims which are attached to and form a part of this application.

In the drawing: Figure 1 is a perspective view of my vanity box, showing the cover removed and also showing a rouge puff which may be furnished with the box; Fig. 2 is a central, vertical sectional view, illustrating the manner in which both the mirror forming the bottom of the box, and the rouge holding pad are secured within the box; Fig. 3 is a horizontal sectional view taken on the line 3—3 of Fig. 2, looking in the direction of the arrows and still further illustrating the mirror and pad fastening means; Fig. 4 is a perspective view of a

modified form of vanity box, illustrating the hinge construction and the manner of mounting a mirror within the cover; Fig. 5 is a central vertical sectional view of the box shown in Fig. 4; Fig. 6 is a vertical central sectional view of a further modified form of box structure.

Corresponding and like parts are referred to in the following description and indicated in all the views of the drawing by the same reference characters.

Referring more specifically to Figs. 1 to 3 of the drawing, it will be seen that my improved vanity box includes a body portion 10, preferably in the form of a cylinder open at its ends. This body is, as a rule, formed of sheet metal although it may be made of any suitable material and at its lower end the body is provided with an inturned annular flange or seat 11, while intermediate its height the body is outstruck to provide an annular bead or shoulder 12. A cover 13 is provided having a downwardly depending marginal flange 14 adapted to engage about the upper edge of the body and rest upon the shoulder 12. This cover is proportioned to frictionally engage about the upper end of the box body and, if desired, the box body may be provided with an outstruck portion 15 to increase this frictional engagement between the box and cover.

A mirror 16 is mounted within the box, resting upon the flange or seat 11 with its reflecting surface directed outwardly. Detachably mounted within the vanity box and resting upon this mirror is a rouge holding pad of the type best disclosed in a copending application filed by me June 14, 1915, Serial No. 34,303. This pad includes a bottom 17, corresponding in shape to but of somewhat less dimensions than the box and having an upwardly and inwardly directed marginal wall 18. A cake of rouge 19 is pressed against the upper face of this pad and beneath the inwardly directed marginal wall which serves to anchor the cake of rouge in place. As a means for detachably securing the rouge holding pad within the box and for, consequently, securing the mirror 16 in place, I provide the wall of the box with a plurality of peripherally spaced indentations 20 forming instruck projections which engage over the lower portion of the marginal wall of the rouge pad. These indentations should be relatively shallow, however, in order that the rouge

holding pad may be forced past them into engagement with the mirror, when assembling the box and in order that, when the rouge is exhausted from the pad, the pad 5 may be forced out of place by pressure exerted against the bottom of the box or mirror and, subsequently, be replaced by a fresh pad. The rouge puff 21 may be provided with each box, if desired, there being room 10 between the cake of rouge and the cover to receive the puff, as will be appreciated from an examination of Fig. 2 of the drawing. In Fig. 6, I have illustrated a construction which is greatly similar to that described but in which the box 22 is formed with a bottom 23 against which the rouge pad 24 seats. In this form of my invention, the internal diameter of the box is somewhat greater than in the form previously 20 described and the peripheral wall of the box is provided with a plurality of spaced indentations 25 forming instruck projections by which the pad may readily pass. A split spring locking ring 26, of resilient 25 wire or other suitable material, is adapted to be located between the marginal wall of the pad and the wall of the box and to engage the wall of the pad and beneath the instruck portions of the wall of the box to 30 anchor the pad in place. Obviously, this ring may be sprung out of place at any time to permit the removal of an exhausted rouge pad and its replacement by a fresh one.

In Figs. 4 and 5 of the drawing, I have 35 illustrated a further form of vanity box including a body 27, preferably formed of sheet metal and provided with a bottom 28. This box body 27 is provided with peripherally spaced indentations 29 by means of 40 which the rouge pad 30 may be anchored in place against the bottom of the box and at its upper edge is formed with spaced parallel slits or clefts 31 opening through the edge of the box and defining the lower portion 45 of a hinge tongue 32, the upper portion of the tongue being in the nature of an ear or tag projecting beyond the edge of the box. With this form of box, I provide a cover 33 having a marginal flange 34 adapted 50 to engage about the upper edge of the box body 27 and formed adjacent its lower edge with a horizontal slot 35 through which the tongue 32 is passed. This tongue 32 is passed outwardly and bent about the marginal portion of the wall 34 between the slot and the free edge of the wall, and is extended downwardly along the marginal wall of the box body and has its free terminal bent upwardly, as shown at 36, to 55 provide a stop which will engage the marginal wall of the box cover when the latter is swung into substantially vertical position, as shown in Fig. 4. By this means, the cover is hingedly connected to the box in such a manner as to be supported so that a

mirror 37, disposed within the cover, will be exposed to convenient view. A retaining ring 38 is soldered or otherwise fixed or formed within the cover in spaced relation to the body, being secured to the marginal wall of the cover and being somewhat greater in internal diameter than the diameter of the mirror in order that the mirror may be passed through this ring to engage against the cover. A split resilient 75 anchoring ring 39, of wire or other suitable material, is sprung beneath the ring 38 and engages this ring 38 and the mirror to lock the mirror in place. The marginal wall of the cover 33, at a point diametrically opposite the hinge, may beoutsprung somewhat, as shown at 40, to provide a lift to facilitate opening of the cover.

Obviously, various minor changes in the method of anchoring the rouge pad in the 80 box, of securing the mirror in place, and the like, may be made and I, therefore, reserve the right to make any changes within the scope of the appended claims without in the slightest degree departing from the 85 spirit of my invention.

Having thus described the invention, what is claimed as new is:

1. A vanity box including a box body having a marginal wall formed with indentations providing interior projections, and a rouge holding pad having an upwardly and inwardly directed marginal wall adapted to be engaged beneath the projections, whereby the pad is anchored in the box.

2. A vanity box including a body open at its ends and provided at its lower end with an inwardly directed annular flange and provided in spaced relation above the flange with indentations providing inward projections, a removable bottom forming element seating within the body of the box and resting upon the flange and a rouge holding pad having an upwardly and inwardly directed marginal wall positioned within the box, the pad having its marginal wall engaged beneath the projections and being thereby anchored in place and against the bottom forming element to hold it in place.

3. A vanity box including a body open at its ends and provided at its lower end with an inwardly directed annular flange and provided in spaced relation above the flange with indentations providing inward projections, a bottom forming element seating within the body of the box and resting upon the flange, a rouge holding pad having an upwardly and inwardly directed marginal wall positioned within the box, the pad having its marginal wall engaged beneath the projections and being thereby anchored in place and against the bottom forming element to hold it in place, and a cover having a marginal flange adapted to frictionally engage about the upper end of the box, the up- 130

per end of the box being outstruck to provide a projection engaging the inner face of the flange.

4. A vanity box including a box body having a bottom formed with an opening and a marginal wall formed with indentations providing interior projections, a removable element seating in the box and closing the opening in the bottom, and a rouge holding pad engaging against the element and locked in the box by the inward projections.

5. A vanity box including a body having an opening in its bottom, a removable element seating within the body and closing the opening, a rouge holding pad seated in the box, and means for anchoring the pad in the box and in engagement with the element.

6. A vanity box including a box body, a

rouge holding pad having an upwardly and inwardly directed marginal wall adapted to seat in the box body, and means including interior projections formed upon the box body for anchoring the pad in place.

7. A vanity box including a body open at its end and provided at its lower end with an inwardly directed annular flange and in spaced relation above the flange with inward projections, a removable bottom seating within the box against the flange, and a rouge holding pad having an upwardly and inwardly directed marginal wall seating within the box against the bottom and engaging beneath the projections whereby both the pad and bottom are anchored in the box body.

In testimony whereof I affix my signature.
WILLIAM G. KENDALL. [I. S.]
